UNITED STATES PATENT OFFICE.

FRANK W. NORTON, OF CEDAR RAPIDS, IOWA.

PHOTOGRAPHIC-PRINTING MACHINE.

1,247,565.

Specification of Letters Patent. Patented Nov. 20, 1917.

Application filed July 19, 1915, Serial No. 40,785. Renewed May 28, 1917. Serial No. 171,574.

To all whom it may concern:

Be it known that I, FRANK W. NORTON, a citizen of the United States, residing at Cedar Rapids, in the county of Linn and 5 State of Iowa, have invented certain new and useful Improvements in Photographic-Printing Machines; and I do hereby declare the following to be a full, clear, and exact description of the invention, such as will 10 enable others skilled in the art to which it appertains to make and use the same.

This invention relates to photographic printing machines, and more particularly to the type of such machines illustrated and 15 described in my former application for patent, No. 844,457, filed June 11, 1914.

The object of this invention is to improve the construction of such machines so as to produce a simple, neat, compact and effi- 20 cient machine for the rapid printing of photographic prints.

The nature of the improvements will fully hereinafter appear, reference being had to the accompanying drawing, in 25 which—

Figure 1 is a side elevation of a machine embodying my invention, except the lower end of the rear leg. Fig. 2 is a plan view of the same. Fig. 3 is a side sectional view, 30 all of the sectional part of the figure being practically central to the machine. Fig. 4 is a section in the line *a b* of Fig. 3, looking toward the rear. Fig. 5 is an enlarged section in the line *c d* of the same figure look- 35 ing downwardly. Fig. 6 is a fragmentary view in perspective, showing the mounting of a narrow negative. Fig. 7 is a section in the line *e f* of Fig. 4, looking toward the right, and illustrating the intermittent cir- 40 circuit closing and breaking device. Fig. 8 is a diagrammatic view illustrating the wir- 45 ing for the lamp and motor.

The first improvement to be noted is in the construction of the main case. This, 45 with the exception of the lid or platen, is made of six main pieces suitably fastened together, as by screws 1. They comprise a front 2, which serves also as the front leg or legs. To this is attached a pair of side- 50 plates 3, which also form the rear legs. Between these, at the back side of the ma- 55 chine, is fitted a pair of angle-plates 4 and 5, which together form the front, top, back and bottom of a rear inclosure for the most of the working parts of the machine,

Aluminium castings are preferably used for these five parts, though iron or other material may be used if desired. The case (ex- 60 cepting the platen, as above noted) is completed by fitting tightly between the side- plates and between the front end 2 and the angle-plate 4 a semi-cylindrical plate 6. This should be of sheet aluminium, or other suitable material with a bright reflecting 65 inner surface, as it serves both as an inclosure for the bottom and sides of the light chamber, and as a reflector for the lamp 7 mounted therein.

To lugs 8 projecting from the upper rear 70 corner of the case, is pivoted the platen 9 by its rearwardly extending arms 10. The platen covers the top of the light chamber completely, so that when closed it entirely excludes the external light therefrom. It 75 should be provided on its under side with a somewhat elastic pad or cushion 11 to press the paper smoothly on the negative 12.

Near the upper, inclined edges of the side- 80 plates are parallel ribs 13 and 14 forming seats respectively for a plate of thick glass 15, such as plate-glass, and a superimposed sheet of window-glass 16, which latter serves as a support for the negative. Over the edge of each side-plate is mounted a 85 clamping strip 17, projecting inwardly to correspond with the ribs above mentioned. Screws 18 admit of the tightening or loosening of the clamping strips, so that an edge 90 of the negative may be slipped under one or both of them, and the strip tightened upon it to hold it in place at that side. If 95 the negative is of the width of the upper portion of the light chamber it will be held by one of these clamps on each side. In case it be a narrow negative one side may be so held, and the other side held by a spring clip 19, of thin material, and adapted to be slipped over the upper edge of the negative-supporting glass and pinch the 100 negative thereon at that side. By using a pair of these clips the negative may be set in the middle of the glass support for it, but in practice it is preferred to use one of the side-clamps for one side of the negative, 105 since its inner edge serves as an accurate side-gage in feeding the paper to printing position. The clamps are very useful also for the purpose of holding the edges of a 110 film negative, and in this case a sheet of clear glass takes the place of a glass nega-

tive, the film being smoothly stretched over the two thicknesses of clear glass, and at the same level as the surface of an ordinary plate.

5 The inclination of the negative is such that if the paper be not supported it will instantly slide off by gravity, as is desirable in discharging the paper after printing. Accordingly the front upper edge of the 10 casing does not rise higher than the upper surface of the negative, and presents no obstruction to the slide of the paper. The lower edge of the paper is held to the printing position by a slide 20 operating between 15 the front-plate and the lower edge of the negative. This space is made by extending inwardly from the front-plate a series of lugs or stops 21, which pass through slots 22 in the slide-plate. The inner edges of 20 the lugs stand at right angles to, and support the glasses 15 and 16 as well as the negative, so that the edges of all are flush with each other. The upper limits of the lugs are flush with the upper surface of 25 the negative, or slightly lower. During the feeding and printing operation the slide rises considerably above the surface of the negative, and being at right angles to the side gage above mentioned, there is presented 30 an accurate squaring gage for the paper as fed. It will be noted that the forward portion of the platen is hollowed at 23 to give room for the slide-plate. The mechanism for tripping the slide-plate will be 35 described presently.

From the hollow 23 of the platen a flange or lip 24 extends downwardly. The purpose of this lip is to shield the eyes of the operator from a momentary flash which 40 would otherwise strike his eyes as the platen suddenly rises.

In the rear inclosure is transversely mounted a large spur gear 25 on its stud 26. Projecting forwardly from this gear 45 is a cam 27, and engaging the cam is a roller 28 attached to an arm 29 fixed to a rock-shaft 30. A lateral lug 31 of this arm takes a connecting-rod 32, which passes through a hole in the top of the casing and engages 50 an arm 33 coöperating with the platen. In practice this is preferably an arm separate from the platen, but hung on its pivot, and attached to the middle of the platen at its other end. This serves to impart central 55 pressure to the platen. It also admits of the use of a slightly flexible arm, which would be difficult to secure in the platen itself. One of its principal advantages is, however, that it is not subject to the crystallizing effect which soon impairs the platen if the connection is direct thereto, it being understood that the platen, in order to give it the least possible weight, is made of aluminium. The action of the cam is to depress 60 the platen to position for closing the light

chamber and holding the print in position. It is opened by a counteractive spring 34, of a type so simple as to require no description.

At the bottom of the light chamber is mounted a long housing 35, in which is pivoted at 36 a lever 37, having at its lower end an upwardly extending arm 38 with a lug or stud 39 engaging a hole 40 in the paper-stop slide-plate. Normally the slide is held by the superior weight of the upper 70 end of the lever in the position shown in Figs. 1 and 3. At this end is a trip-dog 41 held to normal position by a spring 42. In its upward movement, after the point of the cam has passed the roller 28, the lug 31 75 engages this dog, which it passes in its upward movement, and trips the lever, momentarily depressing the paper-stop, and permitting the paper to start down and out of the machine. In its downward movement 80 the lug simply depresses the dog, without disturbing the paper-stop, which has assumed its normal position. As will be seen, one end of the lever 37 passes through a hole 43 into the rear chamber, and the other end 85 through a hole 44 into the light chamber, the holes being masked from the outer light by the housing 35.

In Figs. 4 and 7 is shown the device for opening and closing the lamp circuit, operated by the wheel of which the cam forms a part. Near the periphery of this wheel are set two studs, 45 and 46 to intercept the teeth of a star-wheel 47. The star-wheel connects with a cylindrical circuit-breaker 100 and closer 48, provided with suitable contact brushes 49. In practice the cylinder has four contact spaces, equally disposed, and similarly disposed spaces of insulation, so that there is alternate opening and closing of the 105 circuit as the spaces pass between the brushes. The star-wheel is provided with eight teeth, and is moved one tooth-space with each impact of a passing stud. It will thus be evident that as the main wheel revolves, one stud will close, and the succeeding stud will open the lamp circuit. The studs are so placed as to close the circuit 110 as soon as the platen closes, and to open the circuit before the platen lifts. The time of 115 illumination within those limits may be varied by changing the position of the stud 46. A housing 50 receives the circuit-closer and the stud 51 on which it revolves.

Motion is imparted to the cam-wheel by 120 a small, high-speed motor 52 mounted at the top of the case. A friction-wheel 53 contacts with a friction-disk 54 mounted on a bracket 55. The disk connects with a small cone pulley 56, and this is belted to a larger 125 cone pulley 57 attached to a shaft 58 having a spur pinion 59 at its inner end. This engages an intermediate spur gear 60 attached to another pinion 61, which pinion 130 engages the large spur gear 25. The direc-

tion of motion of the cam-wheel is indicated by the arrow. As soon as the point of the cam passes the roller the platen lifts quickly, the light having first been turned off by 5 breaking the lamp circuit, the exposed paper slides out of the machine, its stop having been depressed, and the operator then has the time occupied by practically a half revolution of the cam in which to feed in a new 10 sheet of paper.

The electrical connections are simple, and are best shown in the diagram, Fig. 8, and by reference to corresponding letters on other figures. It will be understood that 15 the machine will operate at full capacity with the current from an ordinary incandescent lamp socket. In the drawing A and B indicate the wires leading to such a socket. A plug switch C serves to make 20 and break the connection with the machine circuits. One of these leads by the leg D to the lamp, and by the leg E to the rotary intermittent circuit-closer above described. Another leg F leads to the motor, and a 25 connecting leg G to the plug switch. It will thus be seen that the turning on of the current at the plug switch starts the motor, and by its motion the lamp is intermittently switched in and out. When the current is 30 turned off at the plug, both the lamp and motor circuits are broken. The operator may thus know, by the silence of the motor that the lamp is not in action, and heating the machine.

35 Having thus described my invention, I claim:

1. In a photographic printing machine, the combination of a case having a substantially rectangular, vertical inclosure for the 40 working mechanism and a separate light-chamber with a forwardly and downwardly inclined top, a platen conforming to the top of both inclosures, and hinged at its back side, a cam-wheel mounted in the rear inclosure, and a connection of said wheel with the platen forward of its hinges, whereby 45 the cam operates to intermittently depress the platen.

2. In a photographic printing machine, 50 the combination of a case having a forward light-chamber with an inclined top and a rear compartment with a substantially horizontal top, of a platen conforming to said top surfaces and hinged at the back of the 55 case, a spring adapted to move the platen in one direction, and a cam and connection of the cam with the platen forward of the hinges adapted to intermittently move it in the opposite direction.

60 3. In a photographic printing machine, the combination with a case having a light chamber with a forwardly inclined support for a negative, of a platen adapted to close 65 said chamber and press the paper to be printed into printing position, said platen

having a downwardly depending front lip or cowl, and means adapted to intermittently operate said platen to open and close the chamber.

4. In a photographic printing machine, a 70 case having a substantially rectangular rear inclosure adapted to hold and conceal the working mechanism, and a forwardly disposed light chamber inclined downwardly from the top and bottom of the rear chamber, and partitioned therefrom substantially, 75 as set forth.

5. In a photographic printing machine, a case having a substantially rectangular rear compartment for the working mechanism, 80 and a downwardly inclined front chamber provided with means for illuminating the same, the lower part of the light chamber being a single curved sheet of reflecting material. 85

6. In a photographic printing machine, a case composed essentially of six pieces, and comprising a front end and leg piece, a curved and upwardly inclined reflecting body portion extending back from the front, 90 a pair of side and rear leg pieces, and a pair of angled pieces oppositely disposed to form a rear inclosure for the working parts of the machine. 95

7. In a photographic printing machine 95 having an inclined, forwardly disposed printing surface and a front end adapted to support the lower edge of the negative, a slide operating between said front end and the edge of the negative, and adapted to engage the lower edge of the paper as printed, and mechanism adapted to intermittently drop said slide and restore it to normal position. 100

8. In a photographic printing machine 105 having an inclined support for the negative and a front end engaging the lower edge of the negative level with or below the surface thereof, a slide operating between said front end and the negative, and projecting normally above the surface thereof, and mechanism adapted to intermittently drop said slide and to return it to normal position. 110

9. In a photographic printing machine 115 having an inclined support for the negative and a front end engaging the lower edge of the negative level with or below its surface, a slide projecting normally higher than the negative, and operating between its lower edge and said front end, a trip-lever connecting therewith, and a rotating cam-wheel adapted to intermittently actuate said trip-lever. 120

10. In a photographic printing machine 125 having a light chamber with an electric lamp mounted therein, a reciprocating closure for said chamber, a rotating cam-wheel and means for connecting the same operatively with the closure, a suitable light circuit, an intermittently rotatable switch in 130

said circuit provided with a star-wheel, and tappets mounted on said cam-wheel adapted to successively open and close said circuit by rotating the star wheel.

- 5 11. In a photographic printing machine having a light chamber with an electric lamp mounted therein, a reciprocating closure for said chamber, a cam-wheel and connecting mechanism adapted to actuate the closure intermittently, a suitable light circuit, a rotat-
10 ing switch in said circuit provided with a star-wheel, and tappets on said cam-wheel to engage the star-wheel, one of said tappets being adjustable on the cam, to vary the du-
15 ration of the light.
12. In a photographic printing machine having a light chamber with an inclined support for a negative, a slide movable up and down at the foot of said support, and side-strips adapted to clamp the edges of a negative film and to serve as side-guides for the paper to be printed.
13. In a photographic printing machine having a light-chamber with an inclined

negative-supporting glass and ledge to en-
25 gage the lower edge of the negative, a pair of side-strips whose lower faces are nor-
mally flush with the upper surface of the negative, and are adapted to clamp a nega-
30 tive film, a glass insertible in place of a plate negative, and an intermittent closure adapted to press a paper to be printed in po-
sition on said negative.

14. In a photographic printing machine, the combination of an inclined glass sup-
35 port for a negative, a shiftable stop for the lower edge of the paper, a side-clamp for the negative, adapted to serve as a squaring gage for the paper, and a spring clip of thin material adapted to clamp the other side of
40 the negative in place on its support.

In testimony whereof I affix my signature in presence of two witnesses.

FRANK W. NORTON.
